UNITED STATES PATENT OFFICE.

GEORGE H. FORSYTH, OF CHICAGO, ILLINOIS.

WINDOW CONSTRUCTION.

1,299,448.

Specification of Letters Patent. Patented Apr. 8, 1919.

Original application filed October 5, 1908, Serial No. 456,289. Divided and this application filed November 30, 1914. Serial No. 874,751.

To all whom it may concern:

Be it known that I, GEORGE H. FORSYTH, a citizen of the United States, residing at Chicago, in the county of Cook and State of Illinois, have invented certain new and useful Improvements in Window Constructions, of which the following is a specification, the same being a division of my copending application, Serial No. 456,289, filed October 5, 1908.

The invention relates to improvements in window constructions, some of which are more especially, although not exclusively, applicable to car windows; and the invention 15 consists in the several features of improvement in a window construction, all as herein-after described and more particularly pointed out in the claims.

The invention will be readily understood 20 when considered in connection with the accompanying drawings, which illustrate one practical embodiment thereof, and in which—

Figure 1 is a transverse section through a 25 sash member illustrating the invention; and

Fig. 2 is a perspective view showing the same invention in modified form.

Having reference to Fig. 1 of the drawing the sash member 11 is shown as of tubular 30 construction, the integral walls of which overlap marginally and are additionally secured by rivets 12. The material of the sash member is so shaped as to provide a fixed rigid laterally supporting bead 13 and a 35 transverse tie wall forming a fixed rigid shelf or ledge 14 for supporting the glass in the plane thereof. Most of the commercial glass used for glazing purposes is more or less irregular; and a rigid glazing strip, 40 when screwed home, will frequently result in a fracture or break of the glazing. A glass-holding means, therefore, possessing some transverse resiliency or yieldability, is highly desirable. In Fig. 1, 15 designates a 45 removable strip of suitable U-form made of elastic material, with the sides thereof bent or sprung inwardly. The margin of the glass is inserted between the free upper edges of this strip and, to form a cushion seat for 50 the glass, the lower transverse wall of the strip has bent up therefrom spring tongues 16 on which the lower edge of the glass rests. The outer wall of the strip is yieldingly 55 pressed toward the glass by removable glazing means, comprising a series of short strips

forming spring fingers 17 which pass into recesses or apertures 18 in the inner wall of the frame member and at their inner edges adjustably engage spring abutments 19 within the frame member, the outer ends of said 60 fingers thus being elastically pressed against the outer wall of the strip 15.

In Fig. 2 the sash member is similarly formed of a continuous metal sheet having its marginal portions overlapped and interlocked and united in any suitable manner as by brazing at 20. In this case also a fixed glass supporting bead is provided at 20 and a tie wall and glass supporting ledge or shelf at 21.

Here the pane 22 is cushioned on one side by a rubber or other yielding strip confined between one side of the glazing and the inner wall of the bead 20; while the opposite side of the glazing is pressed upon by removable glazing means in the form of a continuous sheet metal strip 23 which has its lower edge notched to provide a series of fingers 24 passing through an apertured countersunk portion or recess 25 of the sash member and secured by suitable means at 26 to the opposite wall of the latter. In all the forms shown in Figs. 1 and 2, the glazing strip is readily removable, in Fig. 1 by simply pulling out the fingers 17, and in Fig. 2 by depressing the strip 23; also the removable glazing means yieldingly supports the glass laterally by reason of the engagement of its lower edge and its bearing in its medial portion against the wall of the recess 18 90 or 25.

It will be evident to those skilled in the art that the various improvements hereinabove described are capable of considerable modification as to details without departing 95 from the invention or sacrificing any of the advantages secured thereby. Hence, I do not limit the invention to the particular forms shown, except to the extent clearly indicated in specific claims.

I claim:

1. In sash construction, the combination with a sash member having its side walls held against spreading at the inner edge of the sash by a transverse wall, the sash member providing a seat for the glass and an integral bead or abutment at one side of the glass seat, and a recess along the other side of the glass seat, of removable glazing means comprising a strip seated within the 105

- recess of the sash, the strip having its upper portion arranged as a lateral support for the glass margin and fulcrumed in its medial portion upon a wall of the recess with its lower portion extending into the recess and frictionally interlocked with a portion of the sash member to preclude accidental displacement.
2. In sash construction, the combination with a tubular sash member having its side walls held against spreading at the inner edge of the sash by a transverse wall serving as a seat for the glass and providing an integral bead or abutment at one side of the glass seat for laterally supporting the glass along one margin thereof and having formed therein a recess along the other side of the glass seat, of removable glazing means comprising a spring strip seated within the recess of the sash, the strip having its upper portion arranged as a lateral support for the glass margin and fulcrumed in its medial portion upon a wall of the recess with its lower portion extending into the recess and offset into interlocked engagement with a portion of the sash member to preclude displacement of the said strip without temporary distortion thereof.
3. In sash construction, the combination with a sash member having its side walls held against spreading at the inner edge of the sash by a transverse wall, the sash member providing a seat for the glass and an integral bead or abutment at one side of the glass seat, and a recess along the other side of the glass seat, of removable glazing means comprising a strip seated within the recess of the sash, the strip having its upper portion arranged as a lateral support for the glass margin and fulcrumed in its medial

portion upon a wall of the recess with its lower portion extending into the recess and frictionally interlocked with a portion of the sash member to preclude accidental displacement, and spring means disposed between the glass and the lateral support therefor to exert constant outward pressure of the glass upon the removable glazing strip.

4. In sash construction, the combination with a sash member having its side walls held against spreading at the inner edge of the sash by a transverse wall, the sash member providing a seat for the glass and an integral bead or abutment at one side of the glass seat and a recess along the other side of the glass seat, of removable glazing means comprising a strip seated within the recess of the sash, the strip having its upper portion arranged as a lateral support for the glass margin and fulcrumed in its medial portion upon a wall of the recess with its lower portion extending into the recess and offset into frictional interlocking engagement with a portion of the sash member to preclude accidental displacement, and spring means disposed between the edge of the glass and its seat and extending on both sides of the glass margin between the glass and the integral support on one side and the upper edge of the removable glazing strip on the other side, whereby to permit the strip to yield out of engagement with the sash and to be removed from the recess.

In testimony whereof I have hereunto signed my name in the presence of two subscribers,

GEORGE H. FORSYTH.
